WIRE TENSIONING APPARATUS
Robert D. Carr, Box 1070, Victoria, Tex. 77901
Filed Dec. 8, 1965, Ser. No. 512,342
3 Claims. (Cl. 25—118)

The present invention relates generally to the casting of articles such as concrete beams and the like, and in particular to an apparatus for putting reinforcing wires under tension prior to casting an article about the wires.

An object of the present invention is to provide an apparatus which lends itself to the efficient tensioning of wires used as reinforcing in concrete articles and the like.

Another object of the present invention is to provide an apparatus which permits the manufacture of concrete beams in any length, with particular emphasis being placed upon the prestressed reinforcing wires which are cast in the beam.

A further object of the present invention is to provide a wire tensioning apparatus for use with casting forms which is simple in structure, one sturdily constructed, one economically feasible, and one which is highly effective in action.

These and other objects and advantages of the present invention will be fully apparent from the following description when taken in connection with the annexed drawings, in which:

FIGURE 1 is a view in section of the apparatus according to the present invention showing it in a condition of use,

FIGURE 2 is a view on an enlarged scale, of a portion of the invention,

FIGURE 3 is a view in section of another portion of the invention,

FIGURE 4 is an elevational view partly in section showing the upper portion of FIGURE 1,

FIGURE 5 is a view taken on the line 5—5 of FIGURE 4,

FIGURE 6 is a view taken on the line 6—6 of FIGURE 4,

FIGURE 7 is a view similar to FIGURE 2 showing the actuating stud being pulled from the cast article,

FIGURE 8 is a view taken on the line 8—8 of FIGURE 7, and

FIGURE 9 is a view of one of the rollers removed from the trackway of FIGURE 6.

Referring in greater detail to the drawings in which like numerals indicate like parts throughout the several views, in FIGURE 1, the apparatus of the present invention is designated generally by the reference numeral 10 and it comprises an elongated tunnel member 12 having a slot 14 in the roof thereof, the roof being designated by the numeral 16.

In FIGURE 2 there is shown the lower portion of a casting form 18 for a concrete beam, the form 18 including a base plate 20, vertical side walls 22 and 24, upper side wall portions 26 and 28, and web wall portions 30 and 32.

The base plate 20 straddles two channel iron members 34 and 36 and is secured thereto by welding or other convenient means. The channel members 34 and 36 are supported upon a block 38 having a slot 40 extending longitudinally therealong and in registry with the slot 14 and the roof 16 of the tunnel member 12.

A trackway 42 is provided in the underface of the roof 16 bridging the slot 14.

The exact form of construction employed in the trackway 42 is immaterial and as shown in FIGURE 2, one form of the trackway 42 consists in a pair of I-beams 44 and 46 arranged in parallel spaced relation and providing means for supporting a rolling carriage 48 between the facing flanges of such I-beams 44 and 46.

2

The carriage 48 includes a solid frame 50, a bottom cushion plate 52, and a wheel 54 at each corner of the frame 50.

Movable within the form 18 is an upright tensioning member 56 having fingers thereon, at 58, for engaging wires or cables 60 as was previously described in my Patent No. 3,013,322.

The member 56 is provided in its lower end with a threaded bore 62 receiving the upper end portion of an actuator stud 64.

An hydraulic cylinder assembly 66, constituting a prime mover, is operatively connected to the stud 64 for effecting a downward pulling movement on the tensioning member 56. The hydraulic cylinder assembly 66 is supported in the tunnel member 12 on conventional means such as rails 68 and 70 embedded in the walls of the tunnel member 12. In FIGURE 3 the assembly 66 is shown in detail and it is seen to consist in an outer cylinder 72 having a bottom plate 74 and a top plate 76 through which extends a sleeve 78 circumscribed about a shaft 80. The lower end of the sleeve 78 carries a piston 82 and conduits 84 and 86 convey air or fluid under pressure from a reversible control valve assembly 88.

Mounted on the end of the sleeve 78 remote from the piston 82 is an open housing 90 through the sides of which is accessible a split nut 92 and a ring 94 surrounding the nut 92 and holding it in position on the shaft 80 which is an extension of the actuating stud 64.

In use, as shown in FIGURES 1 and 4, the hydraulic cylinder assembly 66 is moved along the tunnel member 12 by means of the rolling carriage 48 and it is positioned so as to permit the insertion of the stud 64 upwardly through one of the apertures provided in the form base plate 20. To the upper end of the stud 64 is secured the tensioning member 56 and the cables 60 are engaged under the fingers 58 as in FIGURE 4 before the actuation of the hydraulic cylinder assembly 66.

Adjacent each end of the tunnel member 12 is a support 96 for securing of the adjacent ends of the cables 60. At the other end of the tunnel member 12 is another identical support or other means for holding the cables 60.

Next, the nut 92 is adjusted on the shaft 80 so as to bring the housing 90 into bearing engagement with the carriage 48 with the tensioning member 56 in the relaxed or up position. Now, with the introduction of hydraulic fluid or air under pressure into the upper end of the hydraulic cylinder, the piston 82 will be moved downwardly and the tensioning member 56 will be drawn to the position shown in FIGURE 2, placing all of the cables 60 under a predetermined stress.

The nut 92 may now be used to securely lock the tensioning member 56 in the down position and the concrete or other casting material may be poured into the form 18 and allowed to set.

After the article to be cast has been permitted to set, the stud 64 may be unscrewed from the member 56 and the hole left in the article cast may be filled with cement in the conventional manner.

While only a preferred form of the invention is shown and described other forms of the invention are contemplated and numerous changes and modifications may be made therein without departing from the spirit of the invention as set forth in the appended claims.

65 What is claimed is:

1. In a casting apparatus including an elongated form, one wall of said form being provided with apertures, means adjacent each end of said form for support of reinforcing wires when said wires are suspended within said form, and a tensioning member disposed within said form, said member having wire engaging fingers thereon adapted to

engage said wires, one end of said member having a threaded bore for securement thereto of an actuator stud, a tunnel member extending longitudinally of said form and having a slot in the wall contiguous to the apertured wall of said form, a trackway on said wall in bridging relation with respect to said slot, a carriage rollable on said trackway, a stud extending through said slot and carriage and adapted to have the portion adjacent one end inserted into a selected aperture of said form wall and to be threadably engaged in said tensioning member bore, and a prime mover device connected to said tensioning member adjacent to and engaged with the portion of said stud adjacent the other end thereof, said device being adapted to bear against said carriage so as to effect a pulling movement on said stud when actuated.

2. In a casting apparatus including an elongated form, one wall of said form being provided with apertures, means adjacent each end of said form for support of reinforcing wires when said wires are suspended within said form, and a tensioning member disposed within said form, said member having wire engaging fingers thereon adapted to engage said wires, one end of said member having a threaded bore for securement thereto of an actuator stud, a tunnel member extending longitudinally of and below said form and having a slot in the wall contiguous to the apertured wall of said form, a trackway on said wall in bridging relation with respect to said slot, a carriage rollable on said trackway, a stud extending through said slot and carriage and adapted to have the portion adjacent one end inserted into a selected aperture of said form wall and to be threadably engaged in said tensioning member bore, and a prime mover device connected to said tensioning member adjacent to and engaged with the portion of said stud adjacent the other end thereof, said de-

vice being adapted to bear against said carriage so as to effect a pulling movement on said stud when actuated.

3. In a casting apparatus including an elongated form, one wall of said form being provided with apertures, means adjacent each end of said form for support of reinforcing wires when said wires are suspended within said form, and a tensioning member disposed within said form, said member having wire engaging fingers thereon adapted to engage said wires, one end of said member having a threaded bore for securement thereto of an actuator stud, a tunnel member extending longitudinally of said form and having a slot in the wall contiguous to the apertured wall of said form, a trackway on said wall in bridging relation with respect to said slot, a carriage rollable on said trackway, a stud extending through said slot and carriage and adapted to have the portion adjacent one end inserted into a selected aperture of said form wall and to be threadably engaged in said tensioning member bore, a prime mover device connected to said tensioning member adjacent to and engaged with the portion of said stud adjacent the other end thereof, said device being adapted to bear against said carriage so as to effect a pulling movement on said stud when actuated, and releasable lock means threadably engaged with said stud for holding said tensioning member in the tension applied position.
